(57) **CLAIM**

The ornamental design for a distributor as shown and described.

DESCRIPTION

FIG. 1 is a front view of an ornamental design for a distributor;

FIG. 2 is a left-side view thereof;

FIG. 3 is a right-side view thereof;

FIG. 4 is a rear view thereof;

FIG. 5 is a top view thereof;

FIG. 6 is a bottom view thereof;

FIG. 7 is an upper, right-side front isometric view thereof;

FIG. 8 is a front view of an ornamental design for a distributor of indeterminate extent;

FIG. 9 is a left-side view thereof;

FIG. 10 is a right-side view thereof;

FIG. 11 is a rear view thereof;

FIG. 12 is a top view thereof;

FIG. 13 is a bottom view thereof; and,

FIG. 14 is an upper, front isometric view thereof.

The second embodiment of the distributor depicted herein is shown having break lines along one or more directions in one or more locations. Any portion of the design not shown in the drawings forms no part of the claimed design. The broken lines are included for the purpose of illustrating the portions of the distributor that form no part of the claimed design.
